UNITED STATES PATENT OFFICE.

THOMAS P. SALLEY, OF MOBILE, ALABAMA.

OPERATING MECHANISM FOR DIRIGIBLE HEADLIGHTS.

Application filed March 27, 1926, Serial No. 97,956. Renewed January 29, 1927.

This invention relates to an operating mechanism for dirigible headlights for locomotives and has for its object to provide an operating mechanism whereby the headlight of the locomotive will be maintained in a normal position facing straight ahead when the locomotive is running on a straightaway track but which will be automatically tilted to follow the curve of the railroad when the locomotive is rounding a curve.

An important object of the invention resides in the provision of simple and durable means for properly mounting and maintaining the headlight in normal position and yet causing automatic operation as hereinabove set forth, the operating mechanism being reliable and smooth in operation and easy and comparatively inexpensive to manufacture and install.

Other objects and advantages reside in certain novel features of the construction, arrangement and combination of parts which will be hereinafter more fully described and particularly pointed out in the appended claims, reference being had to the accompanying drawings forming a part of this specification, and in which—

Figure 1 is a fragmentary view in side elevation showing a locomotive headlight equipped with operating mechanism embodying the present invention,

Figure 2 is a view in front elevation further illustrating the operating mechanism, the headlight being removed for the sake of illustration, and

Figure 3 is a view in side elevation of the parts illustrated in Figure 2.

Referring to the drawings the numeral 1 designates a locomotive and the numeral 2 designates the headlight thereof.

The present invention proposes the provision of a horizontally disposed rotatable table or headlight support 3, the same comprising a disc having a bearing at its center which rotatably receives the reduced upper end of a supporting shaft 4, the supporting shaft 4 being suitably secured to the boiler of the locomotive.

50 Rearwardly of the headlight 2 a frame or bracket 5 is provided and has its lower end fastened to the boiler of the locomotive. At its upper end the frame 5 carries a stud shaft 6 on which a gear sector 7 is rotatably supported, the sector 7 having a bearing 8 receiving the stud shaft. A nut 9 prevents ac-

idental endwise displacement of the gear sector. As illustrated in Figure 2 the gear sector has the general form of a triangle, at the apex of which the bearing 8 is located. 60 Bars 10 constitute the sides of the gear sector and are integral with a curved bar 11 having gear teeth 12. A weight supporting arm 15 is fastened, as at 16, to the bars 10 of the sector and the opposite ends of this 65 arm 15 project beyond the sector and carry weights 17, the weights 17 having grooves 18 in which the ends of the arms are fitted. Weights may be adjusted along the arms and are held in adjusted position by means 70 of screws 19 extending through slots 20 provided in the ends of the arms 15, the shanks of the screws having threaded engagement with the weights and the heads of the screws 75 having binding engagement with the ends of the arms. The motion of the gear sector is transmitted to the table or headlight support by means of a gear element 25 pivotally supported intermediate its ends on the frame 5, as at 26, and having one end provided 80 with gear teeth 27 which mesh with the gear teeth 12. The other end of the gear element has gear teeth 28 which mesh with bevel gear teeth 29 provided on the table 3. With 85 this arrangement as long as the locomotive is running on straight track it is level and the headlight will be maintained straight ahead since the weights 17 are adjusted to hold the headlight facing straight ahead when the locomotive is in its normal level 90 position. As is well known curves of railroads are banked; that is, the rail on one side is higher than the rail on the other. 95 As a consequence of this construction when a locomotive rounds a curve it is transversely tilted. This transverse tilting of the locomotive affects the automatic operation of the headlight control means in that it causes the bracket 5 to shift relative to the weight 17, thereby causing the gear element 25 to be moved and the motion of the gear element to be transmitted to the headlight support for rotating the headlight to cause it to follow the curve of the road.

I claim:

1. Operating mechanism for the headlight of a locomotive comprising a rotatable table designed to receive and support the headlight, a stationary frame, a gear sector pivotally supported on said frame, a weight supporting arm fixed to the gear sector and having slots, weights having slots in which the

105

110

slotted portions of the arm are fitted, and fastening means extending through the slots of the arm and engageable with the weights for holding the weights in adjusted position, 5 and a gear element between the gear sector and the table.

2. Operating mechanism for the headlight of a locomotive comprising a rotatable table designed to receive and support the head- 10 light, a stationary frame, a gear sector pivot-

ally supported on said frame, a weight-supporting arm fixed to the gear sector and having portions projecting laterally on the opposite sides of the gear sector, weights adjustably mounted on the opposite end por- 15 tions of the arms, means for holding the weights in adjusted position, and a gear element between the gear sector and the table.

THOMAS P. SALLEY.
